UNITED STATES PATENT OFFICE.

ERNST HEYDENREICH, OF NIEDERSCHÖNEWEIDE, NEAR BERLIN, GERMANY, ASSIGNOR
TO THE FIRM OF KUNHEIM & CO., OF BERLIN, GERMANY, AND THE FIRM OF ALLE-
MEINE RADIÖGEN-AKTIEN-GESELLSCHAFT, OF BERLIN, GERMANY.

RADIOACTIVE PREPARATION.

1,285,704.

Specification of Letters Patent. Patented Nov. 26, 1918.

No Drawing.

Application filed December 11, 1913. Serial No. 805,968.

To all whom it may concern:

Be it known that I, ERNST HEYDENREICH, a citizen of the German Empire, residing at Niederschönweide, near Berlin, Germany, have invented certain new and useful Improvements in Radioactive Preparations, of which the following is a specification.

This invention relates to a radioactive preparation comprising a block or receptacle of porous, inert material and radioactive substance carried by said block or receptacle. Object of the invention is a radioactive preparation of this kind wherein the radioactive substance carried by the inert, porous block consists of a material which by spontaneous decomposition forms that kind of radioactive substance which is the mother substance of emanations that is to say the substance which emits emanations. The radioactive material which in accordance with this invention is preferably used in connection with an inert, solid, porous carrier is radiothorium. The first product of spontaneous decomposition of this material is thorium-X and the thorium-X is the mother substance of the thorium emanation which is formed on spontaneous decomposition of thorium-X. The duration or half-period constant of the radio-thorium is about four years, the half-period constant of the thorium-X about four days and the half-period constant of the thorium-emanation only fifty-two seconds.

In order to obtain the new radioactive preparation the active substance having the property to produce by spontaneous decomposition the mother substance of emanation, preferably radio-thorium, preferably is included in a receptacle of inert, porous material such as kieselguhr, so that the receptacle prevents loss of the active substance. Of course, it is not necessary that such receptacle is on all sides closed by inert, porous walls.

In order to make use of the new radioactive preparation it is put into a liquid having the property to dissolve the mother substance of the emanation of the radioactive substance contained in the porous block but not to dissolve the radioactive substance of the block itself. Preferably the new radio-

active preparation is arranged within the fluid receptacle in such a manner that it bars its outlet so that the fluid drawn off from the receptacle must penetrate through the radioactive porous block and thus obtains an opportunity to dissolve the soluble mother substance of the emanation which has been formed by spontaneous decomposition of the radioactive substance, and to carry it away. It appears from this that it is necessary in order to allow proper use of the new radioactive preparation that the radioactive substance itself and its first product of spontaneous decomposition have different solubility. In the case of radiothorium as radioactive substance and of thorium-X as first product of decomposition this condition is broadly fulfilled. A suitable liquid in the case is a so-called physiological common salt solution, by which is meant a very weak solution of sodium chlorid either rendered slightly alkaline by sodium carbonate, or somewhat acidulated by hydrochloric acid.

I am aware that radioactive preparations are known which comprise a solid block of inert porous material containing incorporated radioactive substances. The purpose of these known radioactive preparations was to permit their emanation to leave the solid block through its pores whereas the mother substance of the emanation was intended to be retained within the body. The present invention relates to a special embodiment of such previously known radioactive preparations and is distinguished from the same by this, that it does not aim at a separation of the emanation from its mother substance and retaining the latter within the inert porous block but that it aims at a separation of the mother substance of the emanation from the block and retaining the radioactive substance which produces the mother substance of the emanation within the block.

What I claim is:—

1. A radioactive preparation comprising a solid body of inert, porous material and a radioactive substance carried thereby, whose first product of decomposition is soluble and is the mother substance of its emanation.

2. A radioactive preparation consisting of a porous block of inert material containing inclosed therein radio-thorium.
3. A radioactive preparation consisting of a block of kieselguhr having a cavity containing radio-thorium.
4. A radioactive solid block containing radio-thorium incorporated in inert porous material, said block arranged within a receptacle containing a liquid adapted to dissolve the thorium-X formed by self-decomposition of said radio-thorium but not to dissolve radio-thorium.
5. A radioactive solid block containing radio-thorium incorporated in inert porous

material, said block arranged within a receptacle containing a physiological common salt solution.

6. A radioactive solid block containing radio-thorium incorporated in inert porous material, said block arranged within a receptacle containing an acidulated weak solution of common salt.

In testimony whereof I affix my signature in presence of two witnesses.

ERNST HEYDENREICH
